Application March 16, 1933, Serial No. 661,120
In Germany March 30, 1932

13 Claims. (Cl. 253—79)

My invention relates to an improved packing for the blade tips of the first row of axially impinged blading which is arranged behind radially impinged blading as in radial flow turbines where 5 the driving medium at first passes through radially impinged blading and afterwards through axially impinged blading.

The number of radially traversed turbine bladings which can be disposed around one another in the radial direction is known to be limited. 10 The bending stresses exerted on the blades and the tangential forces occurring in the head- and root-rings carrying the blades increase with increasing diameter in correspondence with the 15 quickly increasing centrifugal forces to the extent of overstressing the material. It has therefore been the practice to add an axially traversed blading immediately behind the radially traversed blading. If such an arrangement is to give good 20 conditions of flow at the entrance into the axially impinged blading with small structural length the root diameter of the axially traversed moving blades has to be considerably greater than the 25 exit diameter of the last radially traversed moving blades. Hereby the passage from the radial to the axial direction of flow involves a corresponding discontinuity in mean diameter of admission.

Such an arrangement may be used advantageously with turbines having stationary guide blades even with small volumes of working medium passing through the blades per unit of time 30 as turbines with stationary guide blades must have a higher number of stages than counter- 35 running turbines to work up the same pressure drop. Turbines for small volumes passing through their blades have the inherent property that the clearance losses occurring at the tips of the reaction blading—only this is suitable, for radially 40 traversed turbines—exert a predominating influence on the efficiency. As the clearance losses are at least proportional to the clearance cross-section and the clearance cross section is at least 45 proportional to the clearance diameter the clearance losses increase strongly on passing from the radial to the axial direction of flow on account of said discontinuity of diameter if the expansion of the steam does not outweigh the increase in 50 clearance cross section. This however is not yet the case in the first axially traversed stage though it may be in the following stages. This special 55 phenomenon is particularly disadvantageous in that the axially traversed blading is in known constructions provided with an axial joint for assembling and disassembling. As it is known,

axially divided bodies always incline when submitted to alternating heating to deviate at least temporarily from the ring shape. Even such temporary deviations are sufficient to wear away fine packing points and serve to increase substantially the packing clearance and consequently the clearance losses. 5

The present invention has as its objects to provide an improved packing for the first axially impinged blade row and thus to obtain an increased efficiency for the axially impinged blading. 10

According to my invention I recognize that the specific construction of a radially traversed turbine with stationary blading offers the possibility of constructing the first axially arranged series of guide blades as an undivided ring and that furthermore the above-described disadvantages can herewith be removed to a large extent. According to a feature of the invention 20 therefore, I construct the first axially traversed circle of guide blades as a closed ring without axial joints whereby the insertion and removal is effected in an axial direction. This insertion or removal is particularly facilitated in that 25 the guide blade circle in question is connected with the radially traversed guide blade circles arranged immediately in front of it to form a unitary axially insertable and removable system in such a way that this has to be supported against 30 the remaining stationary parts by a single flange only.

My invention results further in an additional improvement of packing the blade tips of the first stationary, axially impinged blade row arranged 35 behind the radially impinged blades. I provide to this end in the space between the root diameter of the axially traversed blading and the last exit diameter of the radially traversed blading a packing consisting of a plurality 40 of radially disposed labyrinth parts which can be slid axially into one another this arrangement having the object to further decrease the leakage losses. So complete a packing is hereby obtained that it is possible to diminish in addition 45 the leakage losses of the appurtenant moving blade series whose working conditions are also not very favorable by diminution of the reaction allotted to it, i. e. the pressure drop to be worked up in it. This results in decreasing the 50 difference in pressure prevailing behind and in front of the moving blade series and consequently the velocity with which the leakage steam is forced through the clearance. Naturally the 55 reaction of the guide blade series, i. e. the pres-

sure drop operating in it, must be correspondingly increased. In consequence of the now extremely effective packing of this row, however, the clearance loss does not increase to a disadvantageous extent even on an increased difference in the pressure prevailing in front of and behind the guide blades. The stationary part of the radially arranged packing advantageously constitutes in this case an extension of the cover band of the guide blade series whereby both together conveniently possess an L-shaped form. I attach the rotatory part of the packing to a disc supporting the radially traversed blading whereby the support may be made flexible as to allow for different expansion during the period of heating up or cooling off. There is no danger in doing so because the thin walled supports of the radially traversed blade groups themselves at once follow all thermal variations and consequently the flexible connection is only slightly stressed whilst in relation to the thermally inert disc which carries the axially traversed blading considerable differences in diameter would occur which would stress the flexible connection highly if it were fastened to said disc.

But with a rigid connection of the rotating parts of the packing to a thin walled disc, i. e. a disc supporting the radially impinged blades constructed in accordance with application Serial Number 600,500 of March 22, 1932, I obtain the further improvement that the increase in the diameters of these parts due to the centrifugal force which makes it difficult—as above said—to keep small clearances in the packing will be kept within comparatively small limits. As the increase in the diameters due to centrifugal force is proportional to the square of the diameter in question this increase would be very considerable with the diameters of the packing unless the radial expansion were limited by means of the rigid connection with a disc of smaller diameter. But I obtain greatest improvement if the rotating packing parts are made integral with a disc supporting the radially impinged blades which is itself capable of following immediately any change in the state of heat of the driving medium.

The drawings show schematically and by way of example a construction according to the inventive idea applied to a radial flow condensing steam turbine with an overhung shaft. In said drawings,

Fig. 1 is a central vertical section through the whole turbine;

Fig. 2 represents the upper part of Fig. 1 in an enlarged scale showing the passage of the steam from the radially impinged blading to the axially impinged blading;

Fig. 3 gives a small part of Fig. 2 with a modified construction of the packing between the two bladings; and

Fig. 4 shows an end view on the flange supporting the axially impinged stationary blades in the direction of the steam flow.

In Fig. 1, the numeral 1 indicates the shaft revolving in the bearing 2 which is enclosed in the housing 3. The shaft 1 supports the disc 4 carrying the rotating blades 5, 6, and 7 and to the disc 4 is fastened another disc 8 carrying the rotating blades 9 which are supported at their other end by means of rings 10. The rotating blades 5, 6, and 7 cooperate with the stationary blades 11, 12 and 13. The rotating blades 9 cooperate with the stationary blades 14. The stationary blades 11 and 12 are supported by an axially divided ring 15, the stationary blades 13 by an ax-

ially undivided flange 16 which has no axial split line and thus keeps its circular shape without warping. The ring 15 and the flange 16 are clamped to the turbine housing 17 by means of the cover 18 through bolts 19 (see Fig. 2). To the flange 16 a stationary disc 20 is fastened which supports the stationary blades 14 the other ends of which are held by the rings 21. The blades 9 and 14 are fastened to the discs 8 and 20 and to the rings 10 and 21 by means of extensions 22 10 and 23 which are inserted in corresponding slots, as shown in Fig. 2.

Steam enters the turbine through pipe 24, flows in a radial direction through the blades 9 and 14, changes to the axial direction and flows through 15 the blades 13, 1, 12, 6, 11 and 5 and finally leaves the turbine at 25.

All the blades shown are of the reaction type there being a difference in pressure before and behind each row of blades. A certain loss occurs 20 along the tips of the blades on account of leakage. Fine points 26, 27, 28 and 29 are for example provided in Fig. 2 to allow for a minimum clearance thus reducing the leakage losses. The clearance at 28 may be made exceedingly small 25 without any danger of injuring the parts. No stripping during changes in the state of heat of the parts will occur as the flange 16 has no axial split line which would cause a tendency for warping. In addition, the shroud of the blades 13 is 30 enlarged to a stationary part 30 of a labyrinth packing the rotating part 31 being supported by the disc 8. A plurality of fine points 32 makes for a very tight joint and decreases the leakage loss in the blade row 13 to such an extent that 35 a greater heat drop may be allotted to the blade row 13 decreasing the corresponding heat drop in the blade row 7 and thus diminishing the difference in pressure before and behind such row and therewith the leakage losses. 40

In Fig. 3 a flexible connection between the rotary part 31 of the labyrinth with the disc 8 is shown by means of a thin extension 33 which is caulked into the disc 8 with a wire 34. Preferably the rotary part 31 is made integral with the 45 disc 8 as shown in Fig. 2 because in this way the part 31 will be subjected to less deformation due to centrifugal force.

The additional labyrinth packing 39/31 does not make the assembling or disassembling of the 50 turbine more difficult. By removing the flange 16 the parts 20 and 13 together with part 30 are removed in an axial direction.

Fig. 4 gives a view on the flange 16 and the disc 20 fastened to it in the direction of the flow 55 of the steam as entering through the pipe 24. The figure has been added to show that the flange 16 is constructed as one single part having no axial split line which construction is essential for obtaining the above described advantages. 60

I claim:

1. In a radial flow turbine in combination, a shaft, a housing, stationary blades adapted to be axially impinged and arranged in one circular row, an annular flange having no axial split line 65 and adapted to support the first row only of said stationary blades, moving blades adapted to be axially impinged and to cooperate with said stationary blades, and a radial flow blading arranged ahead of said stationary blades on a smaller di- 70 meter than said stationary blades.

2. In a radial flow turbine in combination, a shaft, a housing, stationary blades adapted to be axially impinged and arranged in one circular row, an annular flange having no axial split line 75

and adapted to support the first row only of said stationary blades, moving blades adapted to be axially impinged and to cooperate with said stationary blades, and a radial flow blading arranged 5 ahead of said stationary blades, on a smaller diameter than said stationary blades, whereby said annular flange is assembled and disassembled in an axial direction.

3. In a radial flow turbine in combination, a 10 shaft, a housing, stationary blades adapted to be axially impinged by a driving medium and arranged in one circular row, an annular flange having no axial split line and adapted to support the first row only of said stationary blades 15 and to be supported by said housing, a rotating disc supported by said shaft, moving blades adapted to be axially impinged, to be arranged on said rotating disc and to cooperate with said stationary blades, moving blades adapted to be radially impinged, to be arranged in front of said stationary 20 blades, and to be supported by said rotating disc, a stationary disc of smaller diameter than said rotating disc supported by said housing and stationary blades adapted to be radially impinged, to 25 cooperate with said radially impinged moving blades, and to be supported by said stationary disc.

4. In a radial flow turbine in combination, a 30 shaft, a housing, stationary blades adapted to be axially impinged by a driving medium and arranged in one circular row, an annular flange having no axial split line and adapted to support the first row only of said stationary blades and to be supported by said housing, a rotating disc supported by said shaft, moving blades adapted to be axially impinged, to be arranged on said rotating disc and to cooperate with said stationary 35 blades, a second rotating disc of smaller diameter than the first rotating disc supported by said first named rotating disc, moving blades adapted to be radially impinged, to be arranged in front of said stationary blades, and to be supported by said second rotating disc, a stationary disc of smaller diameter than the first rotating disc fixed to said annular flange and stationary blades adapted to be radially impinged, to cooperate with said radially impinged moving blades, and to be supported by 40 said stationary disc.

5. In a radial flow turbine in combination, a 45 shaft, a housing, stationary blades adapted to be axially impinged by a driving medium and arranged in one circular row, an annular flange having no axial split line and adapted to support the first row only of said stationary blades and to be supported by said housing, a rotating disc supported by said shaft, moving blades adapted to be axially impinged, to be arranged on said rotating disc and to cooperate with said stationary 50 blades, a second rotating disc of smaller diameter than the first rotating disc supported by said first named rotating disc, moving blades adapted to be radially impinged, to be arranged in front of said stationary blades, and to be supported by said second rotating disc, a stationary disc of smaller diameter than the first rotating disc fixed to said annular flange and stationary blades adapted to be radially impinged, to cooperate with said radially impinged 55 moving blades, and to be supported by said stationary disc, whereby said annular flange is assembled and disassembled in an axial direction together with said stationary disc.

6. In a radial flow turbine in combination, a 60 shaft, a housing, stationary blades adapted to

be axially impinged by a driving medium and arranged in one circular row, an annular flange adapted to support said stationary blades and to be supported by said housing, a shroud at the inner tips of said stationary blades, a stationary, 5 radially disposed labyrinth packing fixed to said shroud and adapted to be axially engaged with a rotating labyrinth packing, a rotating disc supported by said shaft, a rotating, radially disposed labyrinth packing fixed to said rotating 10 disc and adapted to be axially engaged with said stationary labyrinth packing, moving blades adapted to be axially impinged, to be arranged on said moving disc and to cooperate with said stationary blades, moving blades adapted to be 15 radially impinged, to be arranged in front of said stationary blades, and to be supported by said rotating disc, a stationary disc supported by said housing and stationary blades adapted to be radially impinged, to cooperate with said radially 20 impinged moving blades, and to be supported by said stationary disc.

7. In a radial flow turbine in combination, a 25 shaft, a housing, stationary blades adapted to be axially impinged by a driving medium and arranged in one circular row, an annular flange adapted to support said stationary blades and to be supported by said housing, a shroud at the inner tips of said stationary blades, a stationary, radially disposed labyrinth packing fixed to said shroud and adapted to be axially engaged with a 30 rotating labyrinth packing, a rotating disc supported by said shaft, a rotating, radially disposed labyrinth packing fixed to said rotating disc and adapted to be axially engaged with said stationary 35 labyrinth packing, moving blades adapted to be axially impinged, to be arranged on said moving disc and to cooperate with said stationary blades, the reaction allotted to said moving blades being diminished, while the reaction of 40 the stationary blades is correspondingly increased, moving blades adapted to be radially impinged, to be arranged in front of said stationary blades, and to be supported by said rotating disc, a stationary disc supported by said housing and 45 stationary blades adapted to be radially impinged, to cooperate with said radially impinged moving blades, and to be supported by said stationary disc.

8. In a radial flow turbine in combination, a 50 shaft, a housing, stationary blades adapted to be axially impinged by a driving medium and arranged in one circular row, an annular flange adapted to support said stationary blades and to be supported by said housing, a shroud at the 55 inner tips of said stationary blades, a stationary, radially disposed labyrinth packing fixed to said shroud and adapted to be axially engaged with a rotating labyrinth packing, a rotating disc supported by said shaft, moving blades adapted to be 60 axially impinged, to be arranged on said moving disc and to cooperate with said stationary blades, a second rotating disc fixed to said first named rotating disc by means flexible in radial direction, a rotating radially disposed labyrinth packing 65 supported by said second rotating disc and adapted to be axially engaged with said stationary labyrinth packing, moving blades adapted to be radially impinged, to be arranged in front of said stationary blades, and to be supported by said 70 second rotating disc, a stationary disc fixed to said annular flange and stationary blades adapted to be radially impinged, to cooperate with said radially impinged moving blades, and to be supported by said stationary disc.

9. In a radial flow turbine in combination, a shaft, a housing, stationary blades adapted to be axially impinged by a driving medium and arranged in one circular row, an annular flange adapted to support said stationary blades and to be supported by said housing, a shroud at the inner tips of said stationary blades, a stationary, radially disposed labyrinth packing fixed to said shroud and adapted to be axially engaged with a rotating labyrinth packing, a rotating disc supported by said shaft, moving blades adapted to be axially impinged, to be arranged on said moving disc and to cooperate with said stationary blades, the reaction allotted to said moving blades being diminished, while the reaction of the stationary blades is correspondingly increased, a second rotating disc fixed to said first named rotating disc by means flexible in radial direction, a rotating radially disposed labyrinth packing supported by said second rotating disc and adapted to be axially engaged with said stationary labyrinth packing, moving blades adapted to be radially impinged, to be arranged in front of said stationary blades, and to be supported by said second rotating disc, a stationary disc fixed to said annular flange and stationary blades adapted to be radially impinged, to cooperate with said radially impinged moving blades, and to be supported by said stationary disc.
10. In a radial flow turbine in combination, a shaft, a housing, stationary blades adapted to be axially impinged by a driving medium and arranged in one circular row, an annular flange adapted to support said stationary blades and to be supported by said housing, a shroud at the inner tips of said stationary blades, a stationary, radially disposed labyrinth packing fixed to said shroud and adapted to be axially engaged with a rotating labyrinth packing, a rotating disc supported by said shaft, moving blades adapted to be axially impinged, to be arranged on said moving disc and to cooperate with said stationary blades, a second rotating disc fixed to said first named rotating disc by means flexible in radial direction, a rotating radially disposed labyrinth packing integral with said second rotating disc and adapted to be axially engaged with said stationary labyrinth packing, moving blades adapted to be radially impinged, to be arranged in front of said stationary blades, and to be supported by said second rotating disc, a stationary disc fixed to said annular flange and stationary blades adapted to be radially impinged, to cooperate with said radially impinged moving blades, and to be supported by said stationary disc.
11. In a radial flow turbine in combination, a shaft, a housing, stationary blades adapted to be axially impinged by a driving medium and arranged in one circular row, an annular flange adapted to support said stationary blades and to be supported by said housing, a shroud at the inner tips of said stationary blades, a stationary, radially disposed labyrinth packing fixed to said shroud and adapted to be axially engaged with a rotating labyrinth packing, a rotating disc supported by said shaft, a rotating, radially disposed labyrinth packing integral with said rotating disc and adapted to be axially engaged with said stationary labyrinth packing, moving blades adapted to be axially impinged, to be arranged on said moving disc and to cooperate with said stationary blades, moving blades adapted to be radially impinged, to be arranged in front of said stationary blades, and to be supported by said rotating disc, a stationary disc supported by said housing and stationary blades adapted to be radially impinged, to cooperate with said radially impinged moving blades, and to be supported by said stationary disc.
12. In a radial flow turbine in combination, a shaft, a housing, stationary blades adapted to be axially impinged by a driving medium and arranged in one circular row, an annular flange adapted to support said stationary blades and to be supported by said housing, a shroud at the inner tips of said stationary blades, a stationary, radially disposed labyrinth packing fixed to said shroud and adapted to be axially engaged with a rotating labyrinth packing, a rotating disc supported by said shaft, moving blades adapted to be axially impinged, to be arranged on said moving disc and to cooperate with said stationary blades, a second rotating disc fixed to said first named rotating disc by means flexible in radial direction, a rotating radially disposed labyrinth packing integral with said second rotating disc and adapted to be axially engaged with said stationary labyrinth packing, moving blades adapted to be radially impinged, to be arranged in front of said stationary blades, and to be supported by said second rotating disc, a stationary disc fixed to said annular flange and stationary blades adapted to be radially impinged, to cooperate with said radially impinged moving blades, and to be supported by said stationary disc.
13. In a radial flow turbine in combination, a shaft, a housing, stationary blades adapted to be axially impinged by a driving medium and arranged in one circular row, an annular flange adapted to support said stationary blades and to be supported by said housing, a shroud at the inner tips of said stationary blades, a stationary, radially disposed labyrinth packing fixed to said shroud and adapted to be axially engaged with a rotating labyrinth packing, a rotating disc supported by said shaft, moving blades adapted to be axially impinged, to be arranged on said moving disc and to cooperate with said stationary blades, the reaction allotted to said moving blades being diminished, while the reaction of the stationary blades is correspondingly increased, a second rotating disc fixed to said first named rotating disc by means flexible in radial direction, a rotating, radially disposed labyrinth packing integral with said second rotating disc and adapted to be axially engaged with said stationary labyrinth packing, moving blades adapted to be axially impinged, to be arranged in front of said stationary blades, and to be supported by said second rotating disc, a stationary disc fixed to said annular flange and stationary blades adapted to be radially impinged, to cooperate with said radially impinged moving blades, and to be supported by said stationary disc.

ULRICH MEININGHAUS.
